UNITED STATES PATENT OFFICE.

LAWRENCE J. HESS, OF YOUNGSTOWN, AND MERRILL G. BENJAMIN, OF POLAND, OHIO,
ASSIGNORS TO THE BENJAMIN ENGINEERING COMPANY, OF CLEVELAND, OHIO, A
CORPORATION OF OHIO.

FURNACE CONTROL.

Application filed April 26, 1919. Serial No. 292,954.

To all whom it may concern:

Be it known that we, LAWRENCE J. HESS and MERRILL G. BENJAMIN, both citizens of the United States, residing at Youngstown, county of Mahoning, State of Ohio, and at Poland, county of Mahoning, State of Ohio, respectively, have invented a new and useful Improvement in Furnace Control, of which the following is a full, clear, and exact description, reference being had to the accompanying drawings, forming part of this specification, in which—

Figure 1 is a diagrammatic view showing the invention as embodied in the control for a steam boiler furnace.

Figure 2 is a similar view showing a modification.

Figure 3 is a view similar to Figure 1 but showing the invention as applied to a battery of boilers.

In our co-pending application Serial No. 463,675, filed April 22, 1921, as a continuation in part of the present application, the broader features of our invention have been more clearly described and claimed, the present application relating particularly to the control of the furnace draft and furnace pressure.

The present invention relates to furnace control. One feature of the invention relates to an automatic control of the furnace auxiliaries such as the drafts and stoker. Other features of the invention relate to the control of such furnace auxiliaries in accordance with the demand for steam in the case of a boiler furnace. Another feature of the invention relates to the control of the gas pressure in the combustion chamber of the furnace so as to progressively vary such control for varying rates of combustion. Another feature of the invention relates to the electrical means hereinafter described for effecting the furnace control. Still other features of the invention relate to certain combinations and arrangements of parts hereinafter described, and particularly pointed out in the claims, the advantages of which will be apparent to those skilled in the art from the following description.

Referring first to the embodiment of the invention illustrated in Figure 1:—A steam boiler indicated generally by reference numeral 2, and its furnace by reference

numeral 3. A plurality of such boilers and their furnaces is preferably employed, the steam from such battery of boilers being collected in a common steam pipe or header 4, which, as shown in Figure 2, extends at right angles to the plane of the paper over a plurality of boilers.

The boiler furnace is provided with a forced draft blower 10 which delivers the forced draft to the ash pit 11 under the grate 12. The forced draft fan is driven by an electric motor 13. The waste gas flue 14 is provided with an induced draft fan 15 driven by a motor 16. This waste gas flue is also provided with a damper 17 which is opened or closed by means of an electric motor 18 connected with the damper 17 by means of a worm gear 19. The furnace is also provided with an automatic stoker indicated generally by reference numeral 20, which is driven by an electric motor 21. The forced draft fan, the induced draft fan, the damper and the stoker are duplicated for each of the boiler furnaces of the battery.

The boiler auxiliaries above described, namely, the draft producing and regulating means and the stoker, are automatically controlled in accordance with the demand for steam on the boiler or battery of boilers so as to maintain the output of the boiler or boilers equal to the demand and thereby maintain a substantially constant steam pressure at the same time maintaining the most efficient furnace conditions for its demand. When there is a greater demand for steam, the steam pressure of course will drop. This drop in steam pressure operates through the control, now to be described, to automatically increase the feed of fuel by the stoker and to simultaneously and automatically increase the furnace draft, so that the boiler furnaces are automatically controlled to assume the increased load. Similarly, if the demand for steam decreases, the control operates automatically to cause the stoker to feed less fuel to the fire, and also to cause the draft fans and damper to decrease the draft through the furnace.

The control is an electric control and includes a motor generator set, indicated generally by reference numeral 25, the speed of which is controlled in accordance with the

demand for steam in the boiler by means of a steam pressure actuated regulator 26. The forced draft motor 13, the induced draft motor 16, and the stoker motor 21, are all connected so that their speed varies in accordance with the speed of the motor generator set 25. The motor which opens and closes the damper 17 is connected so that it is controlled both by the motor generator set 25 and also by a compensator device which in turn is controlled by the pressure of the gases in the combustion chamber of the furnace.

The motor 27 of the motor generator set 25 is supplied with current from the current mains 28 and 29, which are preferably the usual direct current mains as employed in factories. The armature of the motor 27 is supplied directly from the mains 28 and 29. The field 30 of the motor 27 is connected through an adjustable rheostat 31 which has a movable contact arm 32. The contact 32 is connected with the arm 33 of the regulator 26. The regulator 26 is connected through a pipe 34 to a steam header 4 of the battery of boilers. The operation of the regulator 26 is such that when the demand for steam decreases and the steam pressure consequently rises above a predetermined point, the arm 33 is raised to raise the contact 32 and thereby decrease the resistance in series with the motor field 30, thereby decreasing the speed of the motor. Conversely, when the demand for steam increases and the steam pressure consequently falls, the arm 33 lowers the contact 32 thereby inserting more resistance in series with the motor field 30 and increasing the speed of the motor generator set.

The regulator 26 is preferably one which has a graduated step by step movement, the arm 33 assuming a number of intermediate positions in accordance with the variations in the steam pressure. Such regulators are old and well known in the art. Examples of such regulators in the patent literature are the Spencer Patents Nos. 338,686 of March 23, 1886 and 479,854 of August 2, 1892. A number of such regulators are on the market such as the well known Spencer regulator, Mason regulator, etc., so that the construction of the regulator need not be described in detail as its construction and operation will be readily understood by any one skilled in the art.

While it is preferred to control the furnace in accordance with the demand for steam by means of a regulator actuated by the steam pressure, other devices responsive to the variations in the demand for steam may be employed. For example, a steam flow meter may be interposed in the main steam line from the boiler or battery of boilers, and so connected with the electrical system that the speed of the motor-generator set will

increase or decrease as the flow of steam increases or decreases, respectively.

The showing in the drawings of the electrical connections is diagrammatic. It is to be understood, of course, that the motor generator set is to be provided with the usual switches, rheostats, fuses, etc., as to be readily understood by any one skilled in the art.

The generator 40 of the motor generator set is mounted on the common shaft with the motor 27 to be driven thereby, as will be readily understood by one skilled in this art. The field 41 of the generator is connected across the feed mains 28 and 29 through a manually adjustable rheostat 42 which may be adjusted to vary the voltage of the generator 40. The generator 40 supplies the auxiliary feed wires 43 and 44. The forced draft motor 13 has its field 45 connected across the main feeder lines 28 and 29 so that the motor field has constant excitation. The armature of the motor 13 is connected across the motor generator feeder lines 43 and 44 to receive variable voltage from the motor generator set. As will be readily apparent, when the speed of the motor generator set increases, the voltage on the lines 43 and 44 also increases and the speed of the forced draft motor 13 will correspondingly increase and increase the forced draft. The manually operable rheostat 46 is inserted in series with the field 45 of the motor 13 so that the speed of such motor may be adjusted. Such adjustment would be made, for example, if it were found that the forced draft fan was either too weak or too strong for the induced draft, or if the forced draft fan for one boiler furnace was weaker or stronger than the forced draft fan for the other boiler furnaces in the battery. Once the rheostat 46 has been adjusted, it requires little, if any, further adjustment, the control of the forced draft fan in accordance with the boiler pressure, being had entirely by means of the automatic electric control.

The armature of the induced fan draft 16 is similarly connected across the variable voltage feeder lines 43 and 44 from the motor generator set 25, and its field 47 is connected in series with a manually adjustable rheostat 48 across the constant voltage main feeder lines 28 and 29. The stoker motor 21 similarly has its armature connected across the motor generator feeder lines 43 and 44 and has its field 49 connected through a manually adjustable rheostat 50 across the constant voltage main feeder lines 28 and 29.

The main feeder lines 28 and 29 and the auxiliary feeder lines 43 and 44 are shown broken off at the left hand side of Figure 1. It is to be understood, however, that such feeder lines are continued to the auxiliaries

of the next boiler furnace, etc., such feeder lines supplying the various motors for all of the boiler furnaces in the battery.

A single motor generator set 25 and its steam actuated controller 26 thereby controls the feed of fuel and rate of combustion for the furnaces of an entire battery.

As will be readily understood from the foregoing description, if the steam pressure in the header 4 rises, the arm 33 and contact 32 of the rheostat will be raised a corresponding amount, thereby reducing the resistance in series with the field 30 of the motor 27 and reducing the speed of the motor generator set. This reduces the voltage on the lines 43 and 44 and correspondingly decreases the speed of the draft fan motors and the stoker motors, thereby decreasing the amount of fuel feed to the fires and the amount of air supply to the fires to support combustion. Similarly, if the steam pressure falls, the motor generator set is speeded up, thereby speeding up the draft fan motors and stoker motors and supplying more coal and air to the furnaces to carry the increased load. Since the regulator 26 assumes intermediate positions in accordance with the steam pressure, the speed of the motor generator set will be similarly affected so that if the demand for steam becomes stabilized, the motor generator set and the several motors for the furnace auxiliaries will assume the correct speed to maintain the fires at the point to just carry the boiler load. The entire system of draft motors and stoker motors may be regulated by means of the hand rheostat 42 which controls the field and, consequently, the voltage of the generator 40. The individual motors may have their speed adjusted by means of the rheostats 46, 48 and 50, one of these rheostats being provided for each motor in the entire battery. By means of these rheostats the forced and induced drafts and the stokers of each furnace may be correlated with each other and also the feed of fuel and rate of combustion of the several furnaces may be correlated. This manual adjustment by means of which the feed of fuel or the draft of one furnace may be adjusted or varied with relation to another furnace, does not interfere with the automatic control of the electrical system by means of which the draft and fuel feed of all of the furnaces are simultaneously controlled. In other words, the manual adjustment of the rheostats 46, 48 and 50 will adjust the draft and fuel feed of one furnace with relation to that of the other furnaces in the battery, while the automatic regulation by means of the common motor generator set 25 varies the rate of combustion and feed of fuel of all the furnaces in accordance with the steam pressure. The common control

system serves to equalize the load upon the several boiler furnaces. This equalization of the load results in the most efficient operation of the battery. Since each boiler can be made to always carry its share of the total load, a greater load can be carried with a given number of boilers than is the case where some boilers carry less than their proper share of the load. It is well known that boilers operated continuously at moderate ratings show better efficiency than boilers operated at variable ratings from low to very high. The life of the furnace brickwork and other parts is greater under the conditions of constant load than otherwise. By providing the means for equalizing the load on all the furnaces, we reduce the variations in rating at which the individual boilers are operated to the actual variation in the station load, thus causing a minimum fluctuation in the rating of any individual boiler furnace.

The draft damper 17 is controlled to open and thereby increase the draft when the steam pressure falls and to close and decrease the draft when the steam pressure rises. The opening and closing of this damper is so correlated with the forced and induced draft fans and with the chimney draft, if any, that the pressure of the gases in the combustion chamber of the furnace progressively decreases as the rate of combustion increases. To effect this correlation, the armature 18 is connected with a reversing switch indicated generally by reference character 60, so that the motor 18 may be driven either forward or backward to open or close the damper 17 through the worm gear 19. The field 61 of the motor 18 is constantly excited and is connected across the main feeder lines 28 and 29. The reversing switch 60 comprises cross connected contacts 62 and 63, which are connected to the lead 64 of the motor 18 and cross-connected contacts 65 and 66, which are connected with the lead 67 of the motor 18. Arranged to make contact with the fixed contacts are two movable contacts 68 and 69 which are connected with the main feeder leads 28 and 29, respectively.

The fixed contacts are carried on a plate 70 which is preferably immersed in the oil in the oil tank 71 to prevent arcing. This plate 70 is longitudinally moved by means of an inclined cam 72, which works in fixed guides and is moved up and down by means of the plunger 73 of the solenoid 74. The plunger 73 is drawn upwardly by the solenoid against the pressure of a spring 75, which is adjusted by means of adjusting screw 76. The solenoid 74 is connected across the feeder lines from the motor generator set 25. When the motor generator set speeds up and its line voltage is thereby increased, the plunger 73 is correspondingly

4

drawn upwardly and the cam 72 shifts the contact carrying the plate 70 to the right, as viewed in Figure 1. The movable contacts 68 and 69 are carried on the lower end 5 of a bell crank 80, the horizontal or upper arm of which rests against a knife edge 81, carried by a hollow downwardly opening bell or float 82. This bell or float 82 floats on the surface of a liquid, preferably oil, in the tank 71. The bell or float is free to move up and down being guided by the guide 83. The upward or downward movement of the bell 82 is caused by the varying pressure of the air or gases therein. Opening inside of the bell 82 is a pipe 84, the other end of which opens into the combustion chamber 85 of the boiler furnace. When the pressure of the gases in the combustion chamber increases, the pressure is 15 communicated to the inside of the bell 82 which rises, thereby moving the movable contacts 68 and 69 to the left, as shown in Figure 1. If the pressure of the gases in the combustion chamber falls, the bell 82 drops and the movable contacts 68 and 69 of the reversing switch 60 are moved to the right as viewed in Figure 1. The bell 82 serves as a compensator and co-operates with the electrically controlled solenoid 74 so 20 that the draft as maintained by the damper 17 is dependent upon two functions of the furnace, namely, the boiler pressure and the pressure of the gases of combustion in the furnace.

30 The expression "function of the furnaces" as used herein, and particularly in the claims, is not intended to be limited to any one function but to include the steam pressure, the pressure of the gases in the combustion chamber, or any other function in accordance with which it is desired to control the furnace.

35 The operation of the damper control is as follows: Suppose that an extra demand for steam comes on the boilers and the steam pressure begins to drop. The regulator 26 operates to speed up the motor generator set thereby increasing the speed of the forced draft fan, the induced draft fan, and the stoker feed. The solenoid 74 raises the plunger 73, moving the contact carrying plate 70 to the right. Simultaneously the increased forced draft increases the pressure in the combustion chamber of 40 the furnace and thereby raises the bell 82, which moves the lower arm of the bell crank 80 to the left, as viewed in Figure 1. The contacts 68 and 69 contact with the contacts 63 and 66 thereby operating the motor 18 to open the damper 17 and lower the pressure in the combustion chamber. As 45 can readily be seen, if the plate 70, which carries the stationary contacts of the reversing switch 60 were fixed in position, the bell 82 would operate the damper so as to

5 maintain a substantially constant pressure of the gases in the combustion chamber for any and all rates of combustion. The action of the solenoid 74 through the cam 72, however, prevents such a constant pressure 70 maintenance and causes the pressure in the combustion chamber 85 to vary with the rate of combustion. As shown in the drawings, the solenoid 74 will operate to decrease the pressure in the combustion chamber of the furnace as the rate of combustion increases, and this is the condition which it is desirable to maintain, particularly with a stoker fired furnace of the type now commonly in use in which we find it advantageous 80 to lower the combustion chamber pressure (or increase the draft over the fire) as the rate of combustion increases. It will be seen, therefore, that the ultimate effect of the automatic regulating system herein disclosed, is to increase the draft and fuel feed in accordance with the demand for steam, and thereby automatically maintain a substantially constant steam pressure, and also to so control the pressure of the gases in 85 the furnace that there is an increased draft over the fire (decreased pressure in the combustion chamber) as the rate of combustion increases.

90 The damper 17 may be manually controlled if desired. For this purpose a double-throw switch 90 is inserted in the leads of the motor 18, by means of which the motor may be disconnected from the automatic reversing switch 60, and connected with a 95 manual reversing switch 91. By throwing the manual reversing switch 91, the operator may open or close the damper.

100 In Figure 2 is illustrated a modification. The operation of the system is essentially 105 the same as that shown in Figure 1, the only essential difference being the control of the forced draft motors, the induced draft motors and the stoker motors, by means of varying their fields, instead of varying the 110 voltage supply to their armatures.

115 Referring to Figure 2:—The unnumbered parts all have the same construction and mode of operation as those shown in Figure 1. The motor generator 25 has its speed controlled by means of the steam actuated regulator 26, as described in connection with Figure 1.

120 Referring first to the motor 13 for the forced draft fan. This motor has its armature connected directly across the constant voltage main feeder lines 28 and 29. The motor has two fields 100 and 101. The main field 100 is connected across the constant voltage main feeder lines 28 and 29 through 125 a manually adjustable rheostat 46. The auxiliary field 101 is the weaker and is arranged to buck the main field 100. The auxiliary field 101 is connected across the variable voltage feed lines 43 and 44, which 130

are supplied with the variable speed motor generator set 25. As the speed of the motor generator set increases upon a drop in steam pressure, as before described, the voltage on the lines 43 and 44 increases. This strengthens the auxiliary field 101 which bucks the main field 100 and thereby weakens the field of the motor 13. This causes the motor 13 to increase in speed and 10 supply more air to the furnace.

Similarly, the induced draft fan motor 16 has two fields, the main field 102, which is connected across the main feeder lines 28 and 29 and a bucking auxiliary field 103 connected across the variable voltage lines 43 and 44 so that when the speed of the motor generator set 25 increases, the speed of the induced draft fan correspondingly increases.

20 In the same way, the stoker motor 21 is provided with two fields 104 and 105, the field 104 serving as the main constant voltage field and the field 105 has a bucking variable voltage field, such fields operating 25 to increase the speed of the stoker motor in accordance with the increase of the speed of the motor generator set 25.

The invention has been set forth in this application as applied to a steam boiler and 30 furnace, but it will be understood that it is equally applicable to boilers utilizing liquids other than water as, for example, the recently developed mercury boiler.

While the invention is illustrated as embodied in a coal fired furnace in which the fuel feed is automatically regulated by varying the speed of the stoker motor, it will be obvious that the fuel feed may be automatically regulated when other fuels, 40 such as gas, oil or pulverized coal, are used. For example, in using gas the gas supply may be suitably throttled, or in case the gas is supplied by a gas producer, the fuel feed may be varied by varying the speed of the 45 blower supplying air to the gas producer. The term furnace as used in the claims, unless otherwise expressly limited therein, is intended as a word of general description and not of limitation, and to include any 50 apparatus which is supplied with fuel and air and in which combustion takes place. For example, the term furnace, when used broadly herein, is intended to include a gas producer which is supplied with fuel and 55 air and in which gas is produced by incomplete combustion. The rate of combustion and fuel feed may be automatically controlled in accordance with the demand for gas, or the gas pressure (corresponding to 60 steam pressure in a steam boiler furnace), or other function of a gas producer type of furnace.

For the sake of simplicity the drawings have been made largely diagrammatic. It is to be understood that the invention is not

limited to its preferred embodiment but that the various instrumentalities diagrammatically illustrated may be variously constructed and that the invention may be embodied in other structures within the scope 70 of the invention as defined in the following claims.

We claim:

1. The combination with a furnace, of means for maintaining an established pressure in the furnace, and means responsive to variations in the demand on the furnace for varying the established pressure to be maintained, substantially as described. 75

2. The combination with a furnace, of draft-controlling means, and means for regulating the draft control to cause a graduated variation in the pressure of the gases in the furnace in accordance with the load carried thereby, comprising two co-operating mechanisms, one controlled in accordance with the pressure of the gases in the furnace and tending to maintain an established pressure therein, and the other controlled in accordance with the demand on the furnace and variable therewith for varying the pressure to be maintained in the furnace, substantially as described. 80 85

3. The combination with a boiler and its furnace, of draft-controlling means, and means for regulating the draft control to vary the pressure of the gases in the furnace, comprising two co-operating mechanisms, one tending to maintain the pressure of the gases substantially constant, and the other serving to progressively vary the pressure of the gases in accordance with the pressure in the boiler or boiler connections, 90 substantially as described. 95

4. The combination with a boiler and its furnace, of a regulator governed by both the pressure in the boiler or boiler connections and the pressure of the gases in the furnace, the regulator including means responsive to the pressure of the gases in the furnace for maintaining an established pressure therein, and means connected with the pressure in the boiler for establishing the pressure to be maintained in the furnace, said means being effective for causing graduated decrements in the pressure to be maintained in accordance with increments in the load carried by the boiler, substantially as described. 100 110 115

5. The combination with a boiler and its furnace, of a regulator for controlling the pressure of the gases in the furnace, the regulator including means responsive to the pressure of the gases in the furnace and tending to maintain an established pressure therein, and the other being effective for establishing such pressure and serving to progressively decrease such established pressure as the rate of combustion increases, substantially as described. 120 125 130

6. The combination with a battery of furnaces, of draft controlling means for each furnace, and means for regulating the draft control, comprising two co-operating mechanisms, one operated in accordance with the pressure of the gases in the individual furnace and tending to maintain an established pressure therein, and the other operated in accordance with a function of the entire battery and effective to establish the pressure of the gases to be maintained in the individual furnaces, substantially as described. 70
7. The combination with a battery of boilers and their furnaces, of draft-controlling means for each furnace, and means for regulating the draft control, comprising two co-operating mechanisms, one controlled by the pressure of the gases in the individual furnace and tending to maintain an established pressure therein, and the other controlled in accordance with the demand on the battery to establish the pressure to be maintained by the first mentioned means, said last-mentioned means being effective to progressively vary the pressure to be maintained as the demand is varied, substantially as described. 75
8. The combination with a battery of boilers and their furnaces, of draft-controlling means for each furnace, and a regulator for such draft-controlling means, each regulator comprising two co-operating mechanisms, one controlled by the pressure of the gases in its furnace and tending to maintain an established pressure therein, and the other controlled in accordance with the demand on the entire battery of boilers and serving to establish the pressure to be maintained by the first-mentioned means, the last-mentioned means being effective to progressively decrease the pressure to be maintained as the demand on the battery increases, substantially as described. 80
9. Furnace control apparatus, including draft-regulating means, an electric motor for operating the same, relatively movable electric contacts for controlling the motor, means dependent on the pressure in the combustion chamber of the furnace for relatively moving the contacts, and means varying with the demand on the furnace for relatively moving the contacts, substantially as described. 85
10. Furnace control apparatus, including draft-regulating means, an electric motor for operating the same, movable and relatively stationary electric contacts for controlling the motor, means actuated by the gases in the furnace for moving a movable contact, and means for shifting the position of a co-operating relatively stationary contact; the draft control motor being effective for changing the pressure of the gases in the furnace, whereby the means responsive to the gas pressure tends to maintain substantially constant a gas pressure determined by the position of the relatively stationary contact, substantially as described. 90
11. Furnace control apparatus, including draft regulating means, an electric motor for operating the same, movable and relatively stationary contacts for the motor, a gasometer bell having a pressure connection with the combustion chamber of the furnace and being operatively connected with a movable contact, the gasometer bell being effective for moving such contact to operate the motor and maintain an established pressure in the furnace, and means for shifting a co-operating stationary contact to establish the pressure to be maintained, substantially as described. 95
12. Boiler furnace control apparatus, including draft-regulating means, an electric motor for operating the same, relatively movable electric contacts for controlling the motor, means dependent on the pressure in the combustion chamber of the furnace for relatively moving the contacts, and means varying with the boiler pressure for relatively moving the contacts, substantially as described. 100
13. The method of operating a furnace, which includes automatically maintaining an established pressure in the combustion chamber of the furnace for a given demand on the furnace, and varying such established pressure with the demand, substantially as described. 105
14. The method of operating a battery of furnaces, which includes automatically establishing in the combustion chambers of the individual furnaces predetermined pressures varying with the demand on the battery, and automatically maintaining in each furnace of the battery the pressure established for any particular demand, substantially as described. 110
15. The method of operating a boiler furnace, which includes automatically establishing in the combustion chamber of the furnace a predetermined pressure varying with the boiler rating, and automatically maintaining the pressure so established, substantially as described. 115
16. The method of operating a battery of boiler furnaces, which includes automatically establishing in the combustion chamber of each furnace of the battery a predetermined pressure varying with the steam pressure in the header of the battery, and automatically maintaining the furnace pressure so established, substantially as described. 120
17. Control apparatus for a battery of furnaces, including fuel-supplying means, a stack damper for each of the furnaces, fuel-supplying control means adapted to 125
- 130

- control the fuel-supplying means for all the furnaces in the battery, damper control means adapted to control the stack dampers for all the furnaces in the battery, means 5 responsive to a function of the battery operatively connected with both the control means and adapted to vary the same to increase or decrease the rate of fuel and air supply with varying demands on the battery, and means for automatically controlling the stack damper of each furnace in the battery in accordance with a pressure condition of such furnace, substantially as described. 10
- 15 18. Control apparatus for a battery of furnaces, including fuel-supplying means, a stack damper for each of the furnaces, fuel-supplying control means adapted to control the fuel-supplying means for all the 20 furnaces in the battery, damper control means adapted to control the stack dampers for all the furnaces in the battery, means responsive to a function of the battery operatively connected with both the control means and adapted to vary the same to increase or decrease the rate of fuel and air supply with varying demands on the battery, means for manually varying the effect of variations of the function-responsive means on at least one of said control means, 25 and means associated with each of the furnaces in the battery for controlling the stack damper of such furnace in accordance with a pressure condition of the furnace, substantially as described. 30 35

In testimony whereof, we have hereunto set our hands.

LAWRENCE J. HESS.
MERRILL G. BENJAMIN.
